(57) **CLAIM**

The ornamental design for the puzzle, as shown and described.

DESCRIPTION

FIG. 1 is a perspective view of the puzzle, in accordance with the invention;

FIG. 2 is a top plan view thereof;

FIG. 3 is a left side view showing the components of the design spaced vertically for ease of illustration;

FIG. 4 is a right side view of FIG. 3;

FIG. 5 is a rear view showing the design components spaced as in FIGS. 3-4, except with the uppermost component superimposed on the nearest planar component; and,

FIG. 6 is a front view of FIG. 5.
